UNITED STATES PATENT OFFICE.

MELVIN L. SEVERY, OF ARLINGTON HEIGHTS, AND GEORGE B. SINCLAIR, OF WINTHROP, MASSACHUSETTS, ASSIGNORS TO CHORALCELO MANUFACTURING COMPANY, A CORPORATION OF MAINE.

MAGNET-RAIL FOR ELECTRIC PIANOS.

1,097,052.

Specification of Letters Patent. Patented May 19, 1914.

Application filed August 7, 1905. Serial No. 273,201.

To all whom it may concern:

Be it known that we, MELVIN L. SEVERY, of Arlington Heights, in the county of Middlesex, State of Massachusetts, and GEORGE B. SINCLAIR, of Winthrop, in the county of Suffolk, said State, both citizens of the United States, have invented certain new and useful Improvements in Magnet-Rails for Electric Pianos, of which the following is a full, clear, and exact description.

This invention is in the field of pianos wherein the strings are vibrated by means of magnetic pulsations communicated thereto, and the object of this invention is the construction of improved means for supporting and moving such magnets by which the magnetic pulsations are conveyed to the strings.

In certain copending applications we have shown, described and claimed, in some instances broadly and in others more specifically, features which are illustrated and described in the present application, but which are not herein claimed or are here claimed only in the specific construction or combination expressed. In other copending applications we have broadly claimed the art of producing musical tones, which art is involved but is not claimed in the present application. All matters set forth and claimed in copending applications filed in our joint names, or in the name of either of us, and not definitely expressed in the claims hereof, are expressly saved and reserved for one or another of said copending applications, in which such matters are claimed or intended to be claimed. Among these copending applications may be noted the following joint applications: Serial No. 273,199, filed August 7, 1905; Serial No. 273,202, filed August 7, 1905; Serial No. 302,331, filed February 23, 1906; Serial No. 377,571, filed June 6, 1907; Serial No. 379,714, filed June 19, 1907; Serial No. 380,987, filed June 26, 1907; Serial No. 537,257, filed January 10, 1910; Serial No. 710,637, filed July 20, 1912; Serial No. 753,013, filed March 8, 1913; Serial No. 745,400, filed January 31, 1913; and Serial No. 757,872, filed March 31, 1913.

Referring to the drawings forming part of this specification, Figure 1 is an elevation of the magnet-rail looking from in front of the piano with which the same is connected, and showing portions of the sides of the piano-case in section. Fig. 2 is a view partly

in elevation and partly in section, of the means for adjusting the pivotal supports of the magnet-rail, showing also the device by which the magnet rail is moved toward and from the piano-strings for the purpose of creating diminuendo and crescendo effects, and otherwise varying the loudness of the music, said view being taken on the line 2--2 looking to the left or in the direction of the arrows and showing the parts more widely separated than in Fig. 3, for greater clearness of illustration. Fig. 3 is a plan view of the magnet-rail, showing the piano-case sides in section. Fig. 3^a is a perspective view of one of the magnet rail supports. Fig. 4 is a sectional elevation of the magnet-rail on larger scale showing adjusting device.

The piano strings 10, as indicated by the dots in Fig. 3, rise in a vertical plane immediately in front of the magnets 20, and though usually placed in groups of two or three to a note, and hence two or three to a magnet, but one string is indicated to a magnet.

The magnet-rail consists of the boards 21, 22 preferably of wood, but of any suitable non-conducting material, and the cast-iron supports 23, 24 carrying said boards. Said supports or bars are each formed with two arms 25 pivoted to adjustable supports 26 clamped by screws 29 to the sides of the piano-case; said screws passing through slots in said supports. By turning the set-screws 28 held in the fixed castings 27, said supports can be accurately adjusted to bring the magnets 20 to the exact positions required to properly actuate the strings. The bar-ends being loosely jointed at 38 and supported thereat by the pivoted brace 39, said bars and boards can be easily moved a limited distance toward and from the strings. Said loose jointing at 38 is, of course, necessary in order to allow a limited longitudinal separation of the two parts of the magnet-rail as they swing on their fixed pivotal points at 25. As this is apparent to anyone skilled in the art, its further description is not needed. The means for thus moving said parts composing the magnet-rail consists of the rock-shaft 34, arm 35, link 36 joining said arm and rail; arm 33, cam-wedge 32, rod 31 and pedal lever 30, in addition to a tension spring 35^a for pressing the parts in

opposition to the action of said cam-wedge. By depressing the end of the pedal lever 30, said cam-wedge is raised, and, by its action on the arm 33, the magnets 20 are moved 5 away from the strings. The descent of said wedge allows the magnets to return to their normal positions with respect to the strings, preferably, in this case, that of strongest influence and loudest tone. To more clearly 10 illustrate the parts in Fig. 2, the arms 25 are shown abnormally elongated; but their correct proportion is that pictured in Fig. 3.

As shown in Fig. 2, the surface of the cam-wedge 32 where it contacts with the end 15 of the arm 33, is not straight, but is so concaved that the beginning of its action upon said arm is much less relative to the movement of said wedge and pedal 30, than at the latter part of said pedal's movement.

20 We design this difference to be sufficient to cause equal arcs of movement on the part of said pedal to produce unequal movements of the magnet rail and hence of the electromagnets 20. It is evident from inspection

25 of Fig. 2, that when the sharper part of the cam-wedge is acting on the arm 33 the electromagnets 20 are farthest from their strings, while the wider parts of the wedge are acting on said arm when the electromagnets 30 are nearer their strings. Inasmuch as the

electromagnets when close to the strings act far more powerfully than when at a considerable distance therefrom, it is manifest that, by adding a slight increase to the distance 35 between a magnet and its string, a decrease may be caused in the magnet's pull thereon equal to adding double such increase to the distance of a magnet from its string when the latter members are farther

40 removed from each other. For example, if a magnet be one sixty-fourth of an inch away from its sonorous body, another sixty-fourth puts it twice as far away, whereas a sixty-fourth of an inch added to the distance

45 of a magnet already an eighth of an inch removed, would be far less noticeable in effect. Hence the curve of the part 32 is shaped as illustrated in Fig. 2 for the purpose of enabling equal movements of the 50 pedal to produce sensibly equal changes in the loudness of the musical tones. By thus arranging the magnet-rail, the magnets in the vicinity of the joint 38 are moved through a proportionably greater distance

55 from the strings than are the ones near either extremity. This might be thought fatal to the operativeness of the device, but is, on the contrary, a vitally important feature. The reasons are that the

60 amplitude of vibration of the highest strings is comparatively limited, and considerable energy is required to vibrate them; consequently the magnets can and should be set normally very close to them. If, now, all the magnets were with-

drawn by the movement of the rail through an equal distance, the differences in effect upon the string's resonance would be much more marked per unit of distance in the cases of the high notes than the lower ones, 70 where the magnets are normally set at a farther distance from the strings because of their greater amplitude of vibration. This law, whereby a rail hinged at 26 and having its upper magnet at a proper distance from said hinge causes the magnets to undergo a sensibly uniform increment or decrement in their effect upon the strings by the normal angular movement of the treble end of the rail, holds good for substantially two-thirds 75 of the notes, but for the lower one-third of the strings, it cannot be applied, but an entirely reverse arrangement must be made. In the case of deep-bass strings, their amplitude of vibration is so very great that, to 80 keep them from striking their magnets when vibrating, the latter must be normally positioned at a considerable distance therefrom. Consequently, if their magnets were withdrawn in the same proportion to which they 85 would be in case the magnet-rail were one inflexible whole and pivoted at its right-hand or treble end, then said magnets would be obliged to remove beyond the ability of 90 effectively influencing their strings. 95

In order that uniform variations of the pedal may produce similar uniform variations in the loudness of the various notes, we have determined that it is necessary that each magnet should have its proper normal 100 distance from its strings and its proper individual variation therefrom as the result of the movement of the pedal. This variation in distance is individual to each magnet, but is proportionate to the angular displacement of a rail hung at its two ends with a properly located and operative joint intermediate thereof, and magnets correctly positioned with respect to their distance from said two ends. 110

We have found, after much experiment and whether supported by theory or not, that the magnet-rail provided with terminal pivots or hinges and properly located intermediate maximum withdrawal is a convenient 115 way to produce the best results as to uniform and proper variations in tone loudness.

As shown in Fig. 2, the cam-wedge 32 has its face suitably concaved for the purpose of perfectly varying the degree of the magnet-rail's departure from the strings relative to the motion of the said wedge and of its 120 pedal by which the latter is operated. This magnet-rail is a very important part of the 125 electric piano set forth in our companion application Serial No. 273199.

Another important feature of said piano is the harmonic controller by means of which various harmonic vibrations can at 130

will be imparted to the strings in place of those normally planned therefor. We have found that certain combinations produce much louder tones than do others, and that to render all the harmonic vibrations substantially uniform, it is desirable to tone down the loudness of a few of the various combinations. Eight being the total number which we find in practice available for use, three of these combinations are all that thus require softening. To effect this softening, we have devised means whereby the movement of the harmonic controller as it reaches said three combinations, automatically removes the magnet-rail a proper distance from the strings. One form of device for this purpose is illustrated in Fig. 4. Here it will be seen that the link 36' which is elsewhere shown unbroken, is centrally jointed, as at 40, and permitted to normally sag at such joint a short distance. This joint is supported by the rod 41 carried at its lower end by a lever 43 pivoted at 45. This lever is in turn supported by a friction-roll 44 riding on the segment cam 46 turning with the harmonic controller. In this segment are three cam-projections 48 located at points to come beneath the roll 44 when the controller brushes 72 touch the contacts 70 appropriated to the three forte harmonic combinations. Hence, every time the harmonic controller-brushes reach any of said three rows of contacts, the cam-projections raise the lever 42 and rod 41, and thereby bring the joint 40 into a right line between the ends of the link 36, consequently moving the magnet-rail the desired distance farther from the strings 10. Although we have illustrated the segment 46 as fixed to the arm 73 carrying the bar 71 to which the brushes 72 are attached; said arm being pivotally supported at 87 and provided with counterbalance spring 77, yet we do not restrict ourselves thereto; inasmuch as said cam may have its independent pivotal support and be operated by suitable connections with the parts which actuate said harmonic controller. The lower end of said rod 41 is preferably threaded and provided with nuts 42 for the purpose of adjusting the normal position of the joint 40, and the normal positions of the magnets with respect to their strings.

What is called fictitious resistance in alternating current circuits we have discovered also occurs in kind in rapidly pulsated currents of constant polarity. For example, a circuit having six ohms resistance at 25 volts would normally take upward of four amperes; yet when the current is broken with sufficient rapidity, the ammeter will show materially less than one-half ampere; behaving as if upward of fifty ohms resistance had been inserted in the line; and, other things being equal, the resistance will vary

with every variation in frequency of interruption. This factor is of such importance that we have found in practice that it outweighs all other considerations. It is manifestly futile to attempt to get any proper gradations in tones or constancy of musical effect unless this factor be met with great care. It will readily be seen that the insertion of such small increments of resistance into the line as would normally occur in small expression-pedal movements would be of no avail unless these exceedingly large, greatly varying fictitious resistances were in some way compensated for. This compensation has been one that has engaged our best attention, and required a wide range of experimentation. Moreover, there are a considerable number of other factors which complicate the proposition; as for example, the law of inverse squares, and its combination with the law governing the magnetic shell; the varying resistances to vibration of differing sonorous bodies; their widely varying possible amplitudes of vibration and volumes; the magnetic lag of the iron; the varying time constants; self-induction, and other considerations.

Among the ways in which we have allowed for these considerations are the following: By varying the windings for the electromagnets controlling the strings, which is more economical and therefore preferable to the insertion of auxiliary resistances; such varying windings being set forth in application Serial No. 380,987; and by varying the distances of the magnets from their respective strings; and by unequally varying their increments of movement for expression purposes, as disclosed in this present application; and also by providing resistances which can be inserted into the lines for musical expression, said resistances varying with respect to the considerations above set forth.

What we claim as our invention and for which we desire Letters Patent is as follows, to wit;—

1. A musical instrument provided with a multiplicity of sonorous bodies of different pitch, electromagnets for the actuation of said bodies, means for delivering properly timed electric pulsations to said electromagnets, and supporting means for the latter, adjacent electromagnets being located at different distances from their respective sonorous bodies.

2. A musical instrument provided with a multiplicity of sonorous bodies of different pitch, electromagnets presenting their poles to said bodies, means for delivering properly timed electric pulsations to said electromagnets, and supporting means for the latter, the electromagnets associated with the sonorous bodies of highest pitch being located more closely thereto than are the bodies of

- intermediate pitches to their associated electromagnets.
3. A musical instrument comprising magnetically attractive sonorous bodies, electromagnets to which said bodies respectively bear the relation of armatures, and means for delivering properly timed electric pulsations to said electromagnets, the latter being located at differing distances from their sonorous bodies.
4. A musical instrument comprising magnetically attractive sonorous bodies, electromagnets to which said bodies bear respectively the relation of armatures, and means for delivering to said electromagnets properly timed electric pulsations, the electromagnets actuating the upper treble sonorous bodies being located nearer to their associated bodies than are the electromagnets lower down the scale to their associated sonorous bodies.
5. A musical instrument comprising magnetically attractive sonorous bodies, electromagnets to which said bodies bear respectively the relation of armatures, and means for delivering properly timed electric pulsations to said electromagnets, the electromagnets actuating the low bass sonorous bodies being located nearer to said bodies than are the intermediate sonorous bodies to their associated electromagnets.
6. A musical instrument comprising tuned sonorous bodies, electromagnets for their actuation, and means for delivering properly timed electric pulsations to said electromagnets, the intermediate electromagnets of the instrument being located farther from their sonorous bodies than are the electromagnets at the extremities of the instrument from their associated bodies.
7. A musical instrument comprising magnetically attractive sonorous bodies, electromagnets to which said bodies bear the relation of armatures, and means for delivering electric pulsations to said electromagnets, the electromagnets of the upper treble sonorous bodies being very close to the latter, the low bass sonorous bodies being sensibly farther from their electromagnets than the treble bodies, and the intermediate sonorous bodies being farther still from their electromagnets.
8. A musical instrument having magnetically attractive sonorous bodies, electromagnets to which said bodies respectively bear the relation of armatures, and means including circuits for delivering to said electromagnets properly timed electric impulses, said electromagnets being placed at different distances from their respective sonorous bodies, such distances being regulated in accordance with the various amplitudes of vibration of the sonorous bodies and the various values of the impedance interposed in the aforesaid circuits as the result of the operating periodicities.
9. The combination of sonorous bodies of different pitch, electromagnets adapted for the actuation of the same, and means under the control of the player for simultaneously moving adjacent electromagnets through unequal distances.
10. A musical instrument provided with sonorous bodies of different pitch, electromagnets adapted for the operation of said bodies, movable supporting means for said electromagnets, and means including a movable controlling member for simultaneously moving said supporting means and electromagnets relative to the associated sonorous bodies, equal movements of said controlling member moving adjacent electromagnets through unequal distances, whereby equal movements of said controlling member produce sensibly equal changes in the loudness of the musical tones educed from said bodies.
11. A musical instrument provided with a multiplicity of sonorous bodies of different pitch, electromagnets to which said bodies are armatures, means for delivering properly timed electric pulsations to said electromagnets, and means for simultaneously shifting said electromagnets relative to said bodies to present certain thereof at greater distances than others from their respective bodies.
12. A musical instrument provided with sonorous bodies of different pitch, electromagnets adapted to actuate the same, an intermediately jointed support, and means for moving said support toward and from said bodies.
13. A musical instrument provided with sonorous bodies of different pitch, electromagnets adapted to operate the same, and means for moving said electromagnets toward and from said bodies constantly presenting certain thereof at greater distances than others from their respective bodies, such distances being greater for the bodies of intermediate pitch and less for the bodies of both higher and lower pitches.
14. A musical instrument provided with sonorous bodies of different pitch, electromagnets adapted to actuate the same, a magnet-rail supporting said electromagnets divided into a plurality of sections, each of which consists of a straight bar, means for supporting said bars out of parallel with each other to present certain of the electromagnets closer to their sonorous bodies than others of the electromagnets are to their said bodies, and means for moving certain ends of said bars toward and from said bodies while the other ends remain substantially stationary.
15. A musical instrument provided with sonorous strings, electromagnets adapted to actuate the same, and an intermediately jointed rail supporting said electromagnets, the ends of said rail being pivotally sup-

ported in the same plane with said strings, and the rail itself being located far enough from said plane to support said electromagnets between itself and the strings.

- 5 16. A musical instrument provided with strings, electromagnets, means for delivering electric pulsations thereto for the actuation of said strings, a magnet rail supporting said electromagnets and pivotally supported 55 at its ends but jointed at an intermediate point, a pivoted brace supporting said joint, and means for moving said joint toward and from said strings.

17. A musical instrument provided with 15 strings, electromagnets, means for delivering electric pulsations thereto for the actuation of said strings, an intermediately jointed magnet-rail carrying said electromagnets, arms rigidly connected with the ends of said 20 rail and pivotally supported on vertical axes in a plane coincident with said strings, and means for moving the jointed part of said rail toward and from said strings.

18. A musical instrument provided with 25 strings, electromagnets, means for delivering electric pulsations thereto for the actuation of said strings, a magnet-rail carrying said electromagnets, and adjustable supports for the ends of said rail, said rail being inter- 30 mediately jointed.

19. A musical instrument provided with sonorous strings, electromagnets controlling the same, means for delivering electric pulsations to said electromagnets, a harmonic 35 controller for varying said pulsations, and means for varying the distances of said electromagnets from said strings by the shifting of said harmonic controller.

20. A musical instrument provided with 40 sonorous bodies, electromagnets controlling the same, means for delivering electric pulsations to said electromagnets, means for switching to said electromagnets a plurality of pulsations of frequencies other than those 45 normal to them, and means controlled by said switching means for automatically varying the distances between said electromagnets and their respective bodies.

21. A musical instrument provided with 50 sonorous bodies, electromagnets controlling

the same, means for delivering electric pulsations to said electromagnets, a harmonic controller for varying said pulsations, and means for automatically varying the distances of said electromagnets from said bodies by the operation of said harmonic controller.

55 22. A musical instrument provided with sonorous strings, electromagnets controlling the same, means for delivering electric pulsations to said electromagnets, a magnet-rail supporting said electromagnets, a harmonic controller adapted by its changes in position to switch any of a plurality of different pulsations to said electromagnets, and connections between said magnet-rail and harmonic controller causing the latter to automatically move the former nearer said strings when shifted to certain positions.

60 23. A musical instrument comprising magnetically attractive sonorous bodies and electric means including electromagnets for the vibration of said bodies, and a magnet rail for the support of said electromagnets, said magnet rail being in a plurality of sections each adjustable relative to said bodies.

65 24. A musical instrument comprising magnetically attractive sonorous bodies and electric means including electromagnets for the vibration of said bodies, and a magnet rail for the support of said electromagnets, said rail being in two sections each adjustable relative to said bodies.

70 25. A musical instrument comprising magnetically attractive sonorous bodies and electric means including electromagnets for the vibration of said bodies, and a magnet rail for the support of said electromagnets, said rail being in two sections each angularly and bodily adjustable relative to said 75 bodies.

In testimony that we claim the foregoing invention, we have hereunto set our hands this 21st day of July, 1905.
